UNITED STATES PATENT OFFICE.

CHARLES F. PECKHAM, OF PROVIDENCE, RHODE ISLAND.

VALVE.

Application filed July 23, 1921. Serial No. 487,088.

To all whom it may concern:

Be it known that I, CHARLES F. PECKHAM, a citizen of the United States, residing at Providence, in the county of Providence and State of Rhode Island, have invented certain new and useful Improvements in Valves; and I do hereby declare the following to be a full, clear, and exact description of the invention, such as will enable others skilled in the art to which it appertains to make and use the same.

This invention relates to a valve, and more particularly to a valve for controlling the emission of a fluid from an orifice of the type wherein the valve is held to its seat to close the orifice by external pressure and opened by the fluid pressure within the orifice when the difference between the fluid and external pressure attains a definite value.

The object of the invention is to provide a novel and improved valve of the character indicated, which opens quickly when the requisite pressure difference is reached and is of a construction which may be manufactured at a minimum expense.

The invention consists in the valve herein-after described and claimed.

The drawing illustrates the invention as embodied in a differential valve adapted to be used in "dry pipe" fire sprinkler systems.

It has heretofore been recognized that valves of the general type in which the valve body is held to its seat to close an orifice by external pressure and moved into an open position by the fluid pressure, within the orifice, would not in practice open quickly nor remain completely open when a predetermined pressure difference between the fluid and external pressure was reached, unless latches, counterweights or intermediate chambers were embodied in the valve construction to offset or counteract the pull exerted upon the valve toward its seat resulting from the development of a region of low pressure under the marginal portion of the valve as the fluid flowed thereunder during the initial opening movements of the valve. This difficulty has led to construction of differential, safety, and similar types of valves which are more or less complicated in design and expensive to manufacture because of the latches, counterweights or intermediate chambers employed.

According to the present invention a construction of valve is provided which op-

erates to practically prevent the development of a region of low pressure under the valve, so that when the requisite pressure difference is reached the valve opens quickly, and, further, the construction of the valve is such that it may be manufactured at a minimum expense.

Referring to the drawing, the fluid is retained within the orifice 10 by a valve disk 12 held to its seat 13 by a comparatively light air pressure within the delivery chamber 14 of the "dry pipe" valve. The valve disk 12 is provided with gaskets 16 for forming fluid-tight joints between the valve and its seat. In order to control the movements of the valve as it opens, the valve disk 12 is pivoted upon a pin 20 mounted in the lugs 22 extended upwardly from the valve seat 13, by a link 24 having a slot 26 which engages the flattened portion 28 of a stud 30 riveted to the valve disk 12, as shown in the drawing. During the opening of the valve, the valve disk swings about the pin 20 as a center into the dotted line 80 position. The usual drip passage 33 is provided to prevent leakage into the delivery chamber 14.

In order to avoid the development of a region of low pressure under the marginal portion of the valve, a disk 42 is secured to the valve disk 12 by links 46 pivoted to both the disk 42 and to the valve disk, as shown. With the valve seat of the inclination shown, the links 46 are of unequal length and are arranged so that the disk 42 assumes a position within the orifice when the valve is closed and normal to the direction of flow of the fluid therethrough. The disk 42 is of smaller diameter than the orifice so that an annular opening 44 is formed between the periphery of the disk and the walls of the orifice, and the lengths of the links are such as to position the disk well within the orifice when the valve is closed.

From the description thus far it will be observed that when the valve starts to open upon the development of a predetermined difference in pressure upon opposite sides of the valve disk 12, and the valve moves a short distance from its seat, the flow of fluid under the valve during its opening movement is restricted by the annular passage 44 surrounding the periphery of the disk 42. The fluid under a given pressure head within the orifice in its passage through this constricted opening 44 and

along the orifice suffers a loss of pressure head so that the body of fluid flowing under the marginal portions of the valve during the opening movement of the valve possesses 5 small pressure head. As the fluid passes under the marginal portions of the valve little or no additional loss of pressure head takes place or can take place, because of the fact that the fluid at this time is under 10 slight pressure head. It will, therefore, be apparent that the formation of the region of low pressure which would in the absence of the disk 42 develop under the marginal portions of the valve during the opening 15 movement thereof is prevented so that, when sufficient pressure difference is attained between the fluid pressure within the orifice and the external pressure, the valve starts to open immediately and continues to open, 20 swinging about the pin 20 into the dotted line position. The disk 42 swings downwardly as the valve opens and assumes the position illustrated in dotted lines after it has been withdrawn from the orifice, so that 25 the liability of the disk again entering the orifice is to a large extent avoided. The link 24 having the slot 26 which engages the flattened portion 28 of the stud 30 serves to maintain the valve disk 12 and 30 links 46 in such position as to permit the disk 42 to swing downwardly under the influence of the weight of the disk 42, as the valve disk 12 moves into the dotted line position. In resetting the valve the operator 35 inserts his hand through the manhole 50, and positions the disk 42 so that it will enter the orifice.

The size of the disk 42 is such as to provide an annular opening 44 between the 40 periphery of the disk and the walls of the orifice of sufficient size to insure free movement of the disk through the orifice under all conditions of operation. It is necessary that this clearance be provided between the 45 disk and the walls of the orifice in order that the disk may not become corroded and adhere to the walls of the orifice, thus preventing the valve from opening when the predetermined pressure difference upon the 50 sides of the periphery has been reached. Furthermore, the size of the opening 44 is such as to cause the fluid, as it flows through the constricted opening 44 and along the walls of the orifice, to lose sufficient head 55 because of the restriction to its flow and because of the hydraulic friction encountered along the walls of the orifice, so that as it passes under the marginal portion of the valve little or no additional loss of pressure 60 head takes place, thus preventing the formation at this point of a region of low pressure. By positioning the disk 42 at greater distances from the valve 12, the size of the annular opening 44 may be increased, 65 for the reason that additional loss of head

takes place during the flow of the fluid along the additional length of the walls of the orifice between the disk 42 and the valve.

From the description thus far it will be observed that all parts of the valve are of 70 standard construction adapted to be manufactured at a minimum expense and that the valve may be assembled easily.

While the invention has been illustrated and described as embodied in a differential 75 valve for use in "dry pipe" fire sprinkler systems, it will be understood that the invention may be embodied in other forms within scope of the following claims:

1. A valve for controlling the emission of 80 a fluid from an orifice comprising a valve body and a disk carried by the valve body at such distance therefrom as to be positioned transversely of and within the orifice during the initial opening movement of the 85 valve, the disk being of smaller diameter than the orifice and spaced from the valve body to form a chamber whereby during the initial opening movement of the valve the fluid is caused to flow through a constricted 90 passage between the periphery of the disk and the walls of the orifice and into the chamber between the disk and the valve body, and to suffer a loss of head, thereby preventing the formation of a region of low 95 pressure under the valve body, and permitting the valve to be instantly and completely opened under the static thrust of the fluid.

2. A differential valve comprising a valve body adapted to be held to its seat by external pressure and opened by the fluid pressure when a definite difference between the fluid and the external pressure is reached, and a disk carried by the 100 valve body at such distance therefrom as to be positioned transversely of and within the orifice during the initial opening movement of the valve and to form a chamber between the disk and the valve body, the disk being of 105 smaller diameter than the orifice whereby during the initial opening movement of the valve, the fluid is caused to flow through a constricted passage between the periphery of the disk and the walls of the orifice and into the chamber between the disk and valve body 110 and to suffer a loss of head thereby preventing the formation of a region of low pressure under the valve body and permitting the valve to be instantly and completely opened under the static thrust of the fluid. 115

3. A valve for controlling the emission of a fluid from an orifice comprising a valve body and a disk pivotally connected to the valve body at such distance therefrom as to be positioned transversely of and within the 120 orifice during the initial opening movement of the valve, the disk being of smaller diameter than the orifice whereby during the initial opening movement of the valve the fluid is caused to flow through a constricted 125

passage between the periphery of the disk and the walls of the orifice, and to suffer a loss of head thereby preventing the formation of a region of low pressure under the 5 valve body, and permitting the valve to be instantly and completely opened under the static thrust of the fluid.

4. A differential valve comprising a valve body adapted to be held to its seat by external pressure and opened by the fluid pressure when a predetermined pressure difference is reached, and a disk pivotally connected to the valve body at such distance therefrom as to be positioned transversely 10 of and within the orifice during the initial opening movement of the valve, the disk being of smaller diameter than the orifice whereby during the initial opening movement of the valve the fluid is caused to flow 15 through a constricted passage between the periphery of the disk and the walls of the orifice, and to suffer a loss of head thereby preventing the formation of a region of low pressure under the valve body, and permitting the valve to be instantly and completely opened under the static thrust of the fluid.

5. A valve for controlling the emission of a fluid from an orifice comprising a valve 30 seat surrounding the orifice, a valve body comprising a flat disk normally held to its seat by external pressure and adapted to be opened by the fluid pressure upon the attainment of a definite difference between the 35 fluid pressure and the external pressure, means for pivotally connecting the valve body and its seat, including a link provided with a slot and a flattened stud secured to the valve body and having its flattened portion received within the slot in the link 40 whereby the valve body is maintained in such position as to permit the valve disk to pivotally move when the valve is opened,

and a disk pivotally connected to the valve body at such distance therefrom as to be positioned transversely of and within the orifice during the initial opening movement of the valve, the disk being of smaller diameter than the orifice whereby during the initial opening movement of the valve the fluid is 45 caused to flow through a constricted passage between the periphery of the disk and the walls of the orifice, and to suffer a loss of head thereby preventing the formation of a region of low pressure under the valve 50 body, and permitting the valve to be instantly and completely opened under the static thrust of the fluid.

6. A differential valve for use in a "dry pipe" fire sprinkler system, comprising a 60 valve casing, an orifice connected therewith and through which water is supplied to the valve casing, a flat valve body normally held in a position to close the orifice by comparatively light air pressure within the valve 65 casing, a disk within the orifice of such size as to form a restricted passage for the flow of water around the disk, and a pair of links pivotally connected to the valve body and disk by which the disk is suspended in a position 70 transversely within the orifice.

7. A differential valve for use in a "dry pipe" fire sprinkler system, comprising a valve casing, an orifice connected therewith and through which water is supplied to the 75 valve casing, a flat valve body normally held in position to close the orifice by comparatively light air pressure within the valve casing, means for pivotally connecting the valve disk to the valve casing, a disk positioned within and transversely of the orifice and of smaller diameter than the orifice, and links by which the disk is suspended 80 from the valve body.

CHARLES F. PECKHAM.
